(57) **CLAIM**

The ornamental design for a can crusher, as shown and described.

DESCRIPTION

FIG. 1 is a perspective view of a can crusher;

FIG. 2 is a perspective view of thereof;

FIG. 3 is a left side view thereof: the opposite side being a mirror image thereof;

FIG. 4 is a top plan view thereof;

FIG. 5 is a bottom plan view thereof;

FIG. 6 is a front elevational view thereof; and,

FIG. 7 is a rear elevational view thereof.

The broken line showing of screw heads and cans in FIG. 1 and portions of the can crusher in FIGS. 4 and 5 is included for the purpose of illustrating portions of the can crusher and form no part of the claimed design.
